UNITED STATES PATENT OFFICE

2,504,300

RULING DEVICE

Robert J. Cashman, Glenview, Ill., assignor, by
mesne assignments, to Research Corporation,
New York, N. Y., a corporation of New York

Original application February 9, 1944, Serial No.
521,594. Divided and this application August
31, 1948, Serial No. 47,019

2 Claims. (Cl. 33—21)

1

This invention relates to a device for ruling grid lines on the interior surface of a cylindrical envelope, such as used for photocells and other like electrical apparatus, and the principal object of the invention is to provide a device of this character which is simple in construction and yet permits the grid lines to be laid down with speed and accuracy.

The present application is a division of my earlier application filed February 9, 1944, Serial No. 521,594, which has matured into Patent No. 2,448,517, issued September 7, 1948.

Further and other objects and advantages will become apparent as the disclosure proceeds and the description is read in conjunction with the accompanying drawings in which

Fig. 1 is a plan view showing a preferred form of the ruling device;

Fig. 2 is an elevational view of the same; and

Figs. 3 and 4 are vertical sectional views taken on the line 3—3 and 4—4 of Figs. 1 and 2 respectively.

Referring now to the drawings, the reference character 99 designates a photocell in the process of fabrication and it comprises a glass envelope upon the interior cylindrical surface of which a photo-conductive material such as described in my prior application hereinbefore referred to is applied over the fine conducting grid. The grid comprises a plurality of parallel conducting lines, alternate ones of which are interconnected to form opposite sides of an electrical circuit with the photo-conductive element interposed as a resistance element between the intercalated grid lines. All of this is described in my prior application before referred to and need not be further described here.

The grid lines are preferably formed of a material known as "Aquadag," manufactured by the Atcheson Colloidal Graphite Company of Port Huron, Michigan, this product being an aqueous colloidal graphite suspension. Other materials may be used, as for example, a graphite pencil.

When the grid is applied to the cell by ruling, it is convenient to use the device shown in Figs. 1 to 4 inclusive. This device consists of a base 90 having a semi-cylindrical bearing 91 at one end adapted to receive a relatively heavy hollow cylinder 92 within which a shaft 85 is rotatably supported by adjustable stop collars 86 and 87. The shaft 85 is hinged at 93 to an arm 94 carrying a bow pen or other marker 95 at its extreme end. The cylinder 92 is provided with

laterally extending trunnion pins 96, which are adapted to snugly seat within notches 97 provided along the upper surface of the semi-cylindrical bearing 91. The notches are spaced apart a distance corresponding to the distance desired between grid lines, which, preferably, is about one-fifteenth of an inch.

The cell which is to receive the grid ruling is clamped to the base 90 by adjustable clamps 98, which firmly hold the envelopes 99 in an appropriate position to receive the end of the arm 94 and the bow pen 95. The lines are ruled onto the interior surface of the envelope 99 by rotating the arm 94 and shaft 85 in the associated bearing 92, and a handle 100 is provided for convenience of manipulation. After a grid line has been ruled, the bearing 92 is moved rearwardly a notch and the next line ruled, and the procedure continues until the desired number of lines has been ruled to produce a cell of the desired resistance values and target area.

In using Aquadag, or any similar conducting material, the suspension should be as concentrated as possible without interfering with proper flowage of the material through the bow pen 95.

I claim:

1. Apparatus for ruling lines at fixed intervals upon the interior cylindrical surface of an envelope comprising means for rigidly holding the envelope, a rotary member provided with a ruling device at one end adapted to project into the envelope, a hollow cylinder rotatably supporting the other end of said member, and means for fixing the longitudinal position of the member within the envelope at regular intervals along the axis of the envelope, said last-named means comprising a semi-cylindrical guideway adapted to receive said cylinder and having notches recessed along its side walls corresponding to said intervals, and trunnions projecting from the cylinder selectively engageable with said notched recesses.

2. Apparatus for ruling lines at fixed intervals upon the interior cylindrical surface of an envelope comprising means for rigidly holding the envelope, a rotary member provided with a ruling device at one end adapted to project into the envelope, a hollow cylinder rotatably supporting the other end of said member, and means for fixing the longitudinal position of the member within the envelope at regular intervals along the axis of the envelope, said last-named means comprising a semi-cylindrical guideway adapted to receive said cylinder and having notches re-

cessed along its side walls corresponding to said intervals, trunnions projecting from the cylinder selectively engageable with said notched recesses, and means for longitudinally adjusting the rotary member relative to the cylinder.

ROBERT J. CASHMAN.
